UNITED STATES PATENT OFFICE.

ARTHUR WRIGHT, OF FOREST HILLS GARDENS, NEW YORK.

CAR-WHEEL CHILLER.

1,174,461.

Specification of Letters Patent.

Patented Mar. 7, 1916.

Application filed May 22, 1915. Serial No. 29,714.

To all whom it may concern:

Be it known that I, ARTHUR WRIGHT, of Forest Hills Gardens, in the county of Queens, and in the State of New York, have 5 invented a certain new and useful Improvement in Car-Wheel Chillers, and do hereby declare that the following is a full, clear, and exact description thereof.

My invention relates particularly to a 10 chiller for use in molding chilled car wheels.

In producing chilled car wheels, it is necessary to mold the tread of the wheel against a bdy. of metal, as for example, 15 iron, so that the heat of the molten metal in the mold will be conducted away so rapidly that the carbon will not have an opportunity to separate out from the molten cast iron in the tread of the wheel, thus 20 producing a chilled surface around the tread of the wheel, which is useful for its extreme hardness. Hitherto, it has been customary to mold such wheels in chillers which have been, in most instances, merely 25 solid rings of iron. Such rings of iron, however, are disadvantageous for use as chillers, as when the molten iron comes into contact with them, they immediately begin to expand, while at the same time, the molten 30 metal in cooling and solidifying immediately begins to contract so that the chiller leaves the surface of the tread portion of the wheel to be chilled, thus defeating the 35 very purpose of the chiller in a large degree, which is to have the chiller remain in contact so as to conduct away the heat from the tread, as rapidly as possible. Furthermore, when the chiller begins to leave the surface of the tread portion of the wheel 40 in this manner, it frequently happens that the chiller becomes separated from said surface a greater distance at one side of the wheel than at the other side thereof, thus producing uneven chilling in a wheel, and 45 consequent imperfections and lack of uniformity in the wheels produced.

In some instances, chillers have been used in which there were a number of bars cast on to the inner face of the chiller and 50 directed toward the tread of the wheel, the main ring of the chiller being provided with a hollow space so that the same could be supplied with steam prior to the pouring of the wheel, and with cold water immedi- 55 ately after the pouring of the wheel, the purpose being to decrease in this way, as

far as possible, the expansion of the chiller when heated by the body of molten metal. Such chillers have, however, been quite ineffective, as the heating and subsequent 60 attempted cooling do not in fact result in any very appreciable cooling of the chillers, owing to the fact that the chillers are in contact with the bodies of highly heated 65 molten metal. Such chillers do not avoid the difficulty of the solid ring chillers, as the surfaces of the chillers even when constructed in this manner would separate from the surfaces of the tread portions of the 70 wheels in the molding operation, and produce the same disadvantageous results and difficulties incident to the use of chillers made of solid rings of iron. Furthermore, this type of chiller in which it is necessary to supply steam, and subsequently cold water 75 required an elaborate system of underground piping to supply the steam and cold water to each individual chiller on the floor where the molding operations were being carried out. As can be seen, this was the cause of 80 very great expense in the installation of the equipment, also a great expense in the maintenance and utilization of the apparatus owing to the necessity of connecting and disconnecting the chillers with 85 the two sets of piping at each molding operation, and owing to the necessity of repairs to the underground piping systems and the many valves and faucets found 90 necessary.

The object of my invention is to provide a car wheel chiller in which there is not the great expansion in the chiller at the time when the molten metal is to be chilled in the mold, but in which there is a positive contraction of the chiller at the time of the molding operation, so that the interior of 95 the chiller may be maintained in close proximity to the tread of the wheel to be chilled.

A further object of my invention is to 100 provide a chiller in which this action is carried out entirely automatically by the action of the chiller itself and without the necessity of applying any extraneous source of energy.

A further object of my invention is to 105 provide a chiller, the diameter of which may be corrected from time to time to take up for the wear or remilling of the inner surface of the chiller.

While my invention is capable of embodiment in many different forms for the

purpose of illustration, I have shown only one form thereof in the accompanying drawings, in which,

Figure 1 is a plan view of a chiller made in accordance with my invention; Fig. 2 is a vertical section of half of a mold for a car wheel, showing my chiller in the mold; Fig. 3 is an enlarged fragmental view partly in section of the top of my chiller; and Fig. 10 4 is a vertical section of my chiller partly in elevation.

In the drawings I have shown a mold, comprising a bottom plate 1, a bottom ring 2 having lugs 3 to receive heads 4 of bolts 5, which clamp a chiller 6 to a top ring 7, having lugs 8 to be engaged by the bolts 5, and a central elevated ring 9 to provide a feeding opening 10 for the molten metal. When the mold is prepared to receive the molten iron, it is provided with a body of sand 11 in the proper form and a central core 12 which forms the only opening in the wheel. When the molten metal has been poured into the mold, and has hardened, it forms a head 11 in the opening 10, and a wheel 13, which are separated from each other by the blow of a hammer, prior to the removal of the wheel 13 from the mold. The chiller is comprised of an outer ring 30 made up of four sections 14, said sections having lugs 15 to receive bolts 16 so as to clamp the sections together and exert the proper clamping force upon the interior parts of the chiller, and so as to adjust, 35 when desired, the interior diameter of the opening in the chiller which is provided to receive the molten metal. On the face of each of the sections 14, there is provided a layer 17 of highly compressed heat-insulating material. Within the layer 17 of heat-insulating material, there is a spiral ring 18 of iron having an upper circular portion 19, and a lower circular portion 20. To the upper circular portion 19 there 40 are pivoted a series of inclined levers 21, having bars 22 on their inner faces directed toward the opening provided for receiving the molten iron. Each of these bars 22 is divided into two subsidiary bars 23 by a 45 slot 24. The pivotal connection between the levers 21 and the ring 19 is formed by screws 25 which connect the levers 21 to the upper circular portion 19. Each of the levers 21 is, furthermore, connected to the lower circular portion 20 by a link 26, screw threaded 50 pivots 27, being provided to connect the levers 21 and the links 26 together. The links 26 are similarly pivoted to the lower circular portion 20 by screws 28. A number 55 of ears 29 are preferably formed on the ring sections 14 so as to position said sections with regard to the remaining parts. In the operation of my invention, when 60 the molten metal is poured into the opening 65 10, and fills the wheel opening therein, the

molten metal comes in contact with the bars 23 thus heating up the bars 23, as well as the spiral ring 18. The parts inside of the insulating layer 17, thus begin to expand against the fixed support provided by the 70 ring sections 14, which are not heated from the body of molten metal in the chiller owing to the heat-insulating layer 17. The mere length of the levers 21 and links 26 will thus produce an inward movement of 75 the bars 23 toward the cooling body of iron in the chiller thus following up the surface of the wheel in the chiller and conveying away the heat from the surface thereof to produce an effective chilling of 80 the tread portion of the wheel. This inward movement of the bars 23 is, however, very much increased and magnified by the longitudinal expansion of the spiral ring 18. The ring 18, owing to the fact that 85 each of the bars 22 has its lever 21 connected to the upper circular portion 19 while its link 26 is connected to the lower circular portion 20, conveys its longitudinal expansion to the toggle lever support for 90 each of the bars 22 and comprising the lever 21 of the link 26 attached thereto, so that the longitudinal expansion of the ring 18 is transformed into an inward movement of the bars 22, which inward movement is, however, further magnified by the toggle lever support for each of said bars 22. In this way, a very effective contraction of the inner surface of the chiller is obtained, thus causing the bars 23 to follow 100 the surface of the wheel in close proximity thereto and effectively chill the same. In case of any wear of the parts or in case it becomes necessary to re-mill the inner surface of the chiller, that is to say, the faces 105 of the bars 23, the internal diameter of the opening in the chiller may be re-adjusted to its original size by screwing up the bolts 16 so as to contract to the desired degree the spiral ring 18 and the various bars 22 110 supported thereon. Furthermore, the provision of these bolts 16 permits the several chillers to be adjusted until all of the chillers in a desired set have exactly the same internal diameter. The arrangement 115 is such, furthermore, that the chiller may be readily taken apart for repairs, and so that individual parts thereof may be readily replaced without the expense of providing an entirely new chiller throughout. 120

While I have described my invention above in detail, I wish it to be understood that many changes may be made therein without departing from the spirit of my invention.

I claim:

1. A car wheel chiller having means for moving its internal surface inwardly comprising a circularly arranged member having circumferential movement and a bar 130

connecting the inner surface of the chiller to said member to convert said circumferential movement into an inwardly directed movement of said surface.

5 2. A car wheel chiller having means for
moving its internal surface inwardly under
the influence of heat from the molten metal
comprising a circularly arranged member
having circumferential movement and a bar
10 connecting the inner surface of the chiller to
said member to convert said circumferential
movement into an inwardly directed move-
ment of said surface.

15 3. A car wheel chiller having means for moving its internal surface inwardly relative to the outer surface of the chiller, comprising a fixed support substantially nonexpansive by the heat from the molten metal.

4. A car wheel chiller having means for
20 moving its internal surface inwardly relative
to the outer surface of the chiller, under
the influence of heat from the molten
metal, comprising a fixed support substantially
25 nonexpansive by the heat from the
molten metal.

5. A car wheel chiller having means for moving its internal surface inwardly relative to the outer surface of the chiller, comprising a fixed support substantially nonexpansive by the heat from the molten metal, and bars associated with the same arranged to be heated from the molten metal.

6. A car wheel chiller having means for moving its internal surface inwardly relative to the outer surface of the chiller, under the influence of heat from the molten metal, comprising a fixed support substantially nonexpansive by the heat from the molten metal, and bars supported from the same arranged to be heated from the molten metal.

7. A car wheel chiller having means for moving its internal surface inwardly relative to the outer surface of the chiller, comprising a fixed support, and a spiral ring carrying bars supported from the same arranged to be heated from the molten metal.

8. A car wheel chiller having means for moving its internal surface inwardly relative to the outer surface of the chiller, under the influence of heat from the molten metal, comprising a fixed support, and a spiral ring carrying bars supported from the same arranged to be heated from the molten metal.

9. A car wheel chiller having means for moving its internal surface inwardly relative to the outer surface of the chiller, comprising a fixed support, and a spiral ring carrying a toggle lever having bars supported from the same arranged to be heated from the molten metal.

10. A car wheel chiller having means for moving its internal surface inwardly relative to the outer surface of the chiller, un-

der the influence of heat from the molten metal, comprising a fixed support, and a spiral ring carrying a toggle lever having bars supported from the same arranged to be heated from the molten metal.

11. A car wheel chiller having means for moving its internal surface inwardly relative to the outer surface of the chiller, comprising a heat insulated fixed support.

12. A car wheel chiller having means for moving its internal surface inwardly relative to the outer surface of the chiller, under the influence of heat from the molten metal, comprising a heat insulated fixed support. 75 80

13. A car wheel chiller having means for moving its internal surface inwardly relative to the outer surface of the chiller, comprising a heat insulated fixed support, and bars supported from the same arranged to 85 be heated from the molten metal.

14. A car wheel chiller having means for moving its internal surface inwardly relative to the outer surface of the chiller, under the influence of heat from the molten metal, comprising a heat insulated fixed support, and bars supported from the same arranged to be heated from the molten metal. 90

15. A car wheel chiller having means for moving its internal surface inwardly relative to the outer surface of the chiller, comprising a heat insulated fixed support, and a spiral ring carrying bars supported from the same arranged to be heated from the molten metal.

16. A car wheel chiller having means for moving its internal surface inwardly relative to the outer surface of the chiller, under the influence of heat from the molten metal, comprising a heat insulated fixed support, 105 and a spiral ring carrying bars supported from the same arranged to be heated from the molten metal.

17. A car wheel chiller having means for moving its internal surface inwardly relative to the outer surface of the chiller, comprising a heat insulated fixed support, and a spiral ring carrying a toggle lever having bars supported from the same arranged to be heated from the molten metal. 110 115

18. A car wheel chiller having means for moving its internal surface inwardly relative to the outer surface of the chiller, under the influence of heat from the molten metal, comprising a heat insulated fixed support, and a spiral ring carrying a toggle lever having bars supported from the same arranged to be heated from the molten metal.

19. A car wheel chiller having means for moving its internal surface inwardly relative to the outer surface of the chiller, comprising a sectional adjacent fixed support substantially nonexpansive by the heat from the molten metal. 130

20. A car wheel chiller having means for moving its internal surface inwardly relative to the outer surface of the chiller, under the influence of heat from the molten metal, comprising a sectional adjacent fixed support substantially nonexpansive by the heat from the molten metal. 35
21. A car wheel chiller having means for moving its internal surface inwardly relative to the outer surface of the chiller, comprising a sectional adjacent fixed support substantially nonexpansive by the heat from the molten metal, and bars supported from the same arranged to be heated from the molten metal. 40
22. A car wheel chiller having means for moving its internal surface inwardly relative to the outer surface of the chiller, under the influence of heat from the molten metal, comprising a sectional adjacent fixed support substantially nonexpansive by the heat from the molten metal, and bars supported from the same arranged to be heated from the molten metal. 45
23. A car wheel chiller having means for moving its internal surface inwardly relative to the outer surface of the chiller, comprising a sectional adjacent fixed support, and a spiral ring carrying bars supported from the same arranged to be heated from the molten metal. 50
24. A car wheel chiller having means for moving its internal surface inwardly relative to the outer surface of the chiller, under the influence of heat from the molten metal, comprising a sectional adjacent fixed support, and a spiral ring carrying bars supported from the same arranged to be heated from the molten metal. 55

der the influence of heat from the molten metal, comprising a sectional adjacent fixed support, and a spiral ring carrying bars supported from the same arranged to be heated from the molten metal.

25. A car wheel chiller having means for moving its internal surface inwardly relative to the outer surface of the chiller, comprising a sectional adjacent fixed support, and a spiral ring carrying a toggle lever having bars supported from the same arranged to be heated from the molten metal. 40

26. A car wheel chiller having means for moving its internal surface inwardly relative to the outer surface of the chiller, under the influence of heat from the molten metal, comprising a sectional adjacent fixed support, and a spiral ring carrying a toggle lever having bars supported from the same arranged to be heated from the molten metal. 50

27. A car wheel chiller having means for moving its internal surface inwardly comprising a toggle lever and means to cause the ends of the links therein to approach each other under the influence of the heat from the molten metal. 60

In testimony that I claim the foregoing I have hereunto set my hand.

ARTHUR WRIGHT.
